CYLINDRICAL GRINDING MACHINE FOR
SHOULDER GRINDING

Lewis A. Williams, Shrewsbury, and Albert C. Racine, Worcester, Mass., assignors to Norton Company, Worcester, Mass., a corporation of Massachusetts

Application December 22, 1937, Serial No. 181,174

5 Claims. (Cl. 51—95)

This invention relates to grinding machines, and more particularly to a safety device for a wheel feeding mechanism in a cylindrical grinding machine.

5 One object of the invention is to provide a simple and thoroughly practical machine for grinding cylindrical work having a plurality of diameters thereon to be ground. A further object of the invention is to provide a safety device 10 for a multi-diameter work grinding machine which prevents the wheel from being fed into the work except when the work table is in a predetermined relationship with the grinding wheel. Another object of this invention is to provide an interlock between the work table and the grinding wheel infeeding movement which prevents the table from traversing longitudinally unless the grinding wheel is withdrawn a sufficient distance to clear the adjacent portion of the work piece. 15 Another object of the invention is to provide a stepped block on the work table and a movable stop member on the base, one of which is moved by and in timed relation with the wheel feeding movement to form an interlock between the table 20 and wheel slide movement to prevent an infeeding movement of the wheel unless the work piece is in a predetermined location relative to the grinding wheel.

The invention accordingly consists in the features of construction, combinations of elements, and arrangements of parts, as will be exemplified in the structure to be hereinafter described, and the scope of the application of which will be indicated in the following claims.

35 In the accompanying drawings, in which is shown one of the possible embodiments of the mechanical features of this invention,

Fig. 1 is a fragmentary front elevation of a grinding machine;

40 Fig. 2 is a fragmentary plan view, on an enlarged scale, of the wheel feeding mechanism;

Fig. 3 is a fragmentary cross sectional view, taken approximately on the line 3—3 of Fig. 1, showing the wheel slide and work table in elevation and the base in cross section;

45 Fig. 4 is a fragmentary end elevation and sectional view, taken approximately on the line 4—4 of Fig. 1, showing the safety mechanism which is actuated by the wheel feeding mechanism;

50 Fig. 5 is a fragmentary sectional view, on an enlarged scale, taken approximately on the line 5—5 of Fig. 4; and

Fig. 6 is a fragmentary cross sectional view, taken approximately on the line 6—6 of Fig. 5.

55 A cylindrical grinding machine has been illus-

trated in the drawings having a base 10 which supports a transversely movable wheel slide 11 on the usual V-way and flat way (not shown). The wheel slide 11 supports a rotatable grinding wheel 14 which is mounted on one end of a rotatable wheel spindle 15. The spindle 15 is journalled in suitable bearings (not shown) in the wheel slide 11.

The grinding wheel 14 and its supporting spindle 15 may be rotated in a suitable manner, such as by means of an electric motor 16 mounted on the upper surface of the wheel slide 11. A motor armature shaft 17 is provided at its outer end with a multiple V-groove pulley 18 which is connected by multiple V-belts 19 with a pulley 20 mounted on the outer end of the wheel spindle 15. It will be readily apparent from the foregoing disclosure that rotation of the motor 16 is transmitted to rotate the wheel spindle 15 and the grinding wheel 14.

The base 10 also supports a longitudinally reciprocable work supporting table 21 which is mounted on the usual flat way 22 and V-way 23 and is arranged to slide longitudinally relative to the transversely movable wheel slide 11 and grinding wheel 14.

The work table 21 is provided with a rotatable work support comprising a headstock 24 having a headstock center 25 which is arranged rotatably to support one end of a cylindrical work piece. A 20 footstock 26 is also mounted on the table 21 and carries a footstock center 27 which serves as a rotatable support for the other end of a work piece 28. The headstock center 25 and footstock center 27 serve rotatably to support the work piece 28 for a grinding operation. A work driving dog 29, of any well known type, is clamped on the end of the work piece 28 and is arranged to be engaged and driven by a driving pin 30 carried by a rotatable driving plate 31 on the headstock 24. The work piece 28, as illustrated, is a piece having several cylindrical portions of different diameters to be ground, namely portions 35 36 and 37.

The table 11 is arranged for a longitudinal 45 reciprocal movement on the base 10 and may be moved either manually or automatically under power, as will be hereinafter described. A manual table traversing mechanism has been illustrated comprising a manually operable traverse wheel 40 which is mounted on the outer end of a rotatable shaft 41. A gear 42 carried by the shaft 41 meshes with a gear 43 which is mounted on a rotatable shaft 44. The shaft 44 also carries a gear 45 meshing with a rack bar 46 depending 50 55

from the work supporting table 21. By rotation of the traverse wheel 40, the table 21 may be caused to traverse longitudinally relative to the base 10 so as to position and grind either the portion 35, 36 or 37, as is desired.

If desired, the table 21 may be reciprocated automatically by means of a power driven mechanism, such as that shown in the prior U. S. patents to Norton No. 762,838 dated June 14, 1904, and Wilcox, et al. No. 1,197,700, dated September 12, 1916, to which reference may be had for details of disclosure not found herein. A stepped driving pulley (not shown) contained within the casing 50 serves to rotate a shaft 51 which drives a table driving and reversing mechanism contained within the casing 52 (Fig. 1). The driving and reversing mechanism includes a reversing clutch which is arranged to be actuated by a pivotally mounted reversing lever 53 which may be actuated automatically by adjustable table dogs (not shown) mounted on the front edge of the table 21.

The grinding wheel 14 may be fed transversely toward and from the work piece 28 by a wheel feeding mechanism which may comprise a half nut 60 depending from the wheel slide 11 which meshes with a rotatable feed screw 61 which is journaled in suitable bearings (not shown) at its rear end. The front reduced end portion 62 of the feed screw 61 is slidably keyed in a sleeve 63 journaled in a bearing 64 in the base 10. The sleeve 63 has formed integral therewith a shaft 65 which carries a gear 66 on its outer end. The gear 66 meshes with a small gear 67 which is carried by a rotatable sleeve 68 and has formed integral therewith a gear 69. A manually operable hand feeding device 70 is connected to rotate the gear 69 by means of a micrometer adjusting mechanism 71 which is similar in construction to that shown in the prior U. S. Patent No. 1,197,700 above referred to, to which reference may be had for further details of disclosure. By manipulation of the micrometer adjusting mechanism, a multi-stop ring 77 supported on the periphery of the feed wheel gear 69 may be adjusted precisely to locate and size the spaced multi-diameter portions of the work piece being ground. A stop pawl 75 pivotally mounted on a stud 76 is arranged to engage adjustable stops carried by the stop ring 77.

In grinding work pieces having several diameters to grind, it is desirable to use a multi-stop device which may comprise the multi-stop ring 77 which is mounted on the periphery of the gear 69 of the feed mechanism. The multi-stop ring 77 is arranged to carry a plurality of adjustable stop blocks 78, 79 and 80 which are adjustably mounted in a groove cut in the periphery of the multi-stop ring 77. The adjustable stop blocks 78, 79 and 80 are adapted to cooperate with the stop pawl 75 so as to stop the infeeding movement of the grinding wheel when it has fed into the work to a predetermined extent.

In grinding shouldered work or multi-diameter cylindrical work of the type illustrated in the drawing, it is desirable to provide a suitable safety device to prevent the grinding wheel from being fed in except when the proper portion of the work piece 28 is opposite the grinding wheel 14, and to prevent a longitudinal traversing movement of the work table 21 unless the grinding wheel 14 is withdrawn a sufficient distance to clear the adjacent portion of the work piece 28. To accomplish this result, a multi-stepped block 85 is adjustably mounted on the front edge of the table

21. This block 85 has a series of steps 86, 87 and 88 which correspond to the several diameters 37, 36 and 35, respectively, on the work piece 28 to be ground. In order to prevent the grinding wheel 14 from being fed into the work piece 28 at the wrong time, a suitable interlock is provided between the table 21 and the grinding wheel feeding mechanism. This mechanism comprises a pivotally mounted lever 90 which is supported on a stud 91 on the base 10. The lever 90 is provided with an aperture 92 which is arranged to receive the inner end of a screw threaded member 93. The screw threaded member 93 has a series of V-shaped notches 94, preferably four in number, cut at a point adjacent to its inner end. A pair of pointed set screws 95 and 96 are screw threaded into the lever 90 on diametrically opposite sides of the screw threaded member 93 and have their points engaging the opposed notches 94 cut in the screw threaded member 93. In order to move the pivoted stop arm 90 in timed relation with the rotation of the feed wheel 70, a gear 100 is keyed to a rotatable sleeve 101 which is in turn supported in the anti-friction bearing 102. The bearing 102 is supported in the bracket 103 which is in turn fixedly mounted on the base 10. The sleeve 101 is held against endwise movement at one end by a flange formed integral with the sleeve 101 and at the inner end by an adjustable collar 104 screw threaded onto a threaded portion on the inner end of the sleeve 101. The sleeve 101 has its inner aperture threaded to mesh with the screw threaded member 93. A gear 105 is formed integral with the multi-stop ring 77 and meshes with the gear 100.

When the manually operable feed wheel 70 is rotated to feed the grinding wheel 14 toward the work piece 28, rotation of the multi-stop ring 77 and gear 105 is transmitted to the gear 100 to rotate the sleeve nut 101. The rotation of the sleeve nut 101, through its internal thread transmits an endwise movement to the screw threaded member 93 which in turn rocks the lever 90 about its pivot 91 so that the upper end of the lever 90 moves toward and from the stepped stop bar 85 which is carried by the table 21.

It will be readily apparent from the foregoing disclosure that unless the table 21 is located so that the upper end of the lever 90 is in position to engage the portion of the stepped bar 85 corresponding to the portion of the work piece 28 which is in opposite the grinding wheel, the grinding wheel and its supporting slide cannot be fed forward to grind the wrong portion of the work. Similarly, when the grinding wheel is in an operative position, such as is shown in Fig. 1, to grind the portion 37 of the work piece 28, the table 21 cannot be traversed longitudinally toward the right to damage the enlarged portion 36 of the work piece 28 due to the fact that the step 87 on the stop bar 85 serves as a stop to prevent longitudinal movement of the table until the grinding wheel has receded a sufficient distance to clear the periphery of the shoulder 36.

A separate multi-stop bar 85 is provided for each type of work piece which is to be ground in the machine. The longitudinal spacing of the steps on the bar as well as the depth of each successive step is made to correspond with the multi-diameter portions of the work piece to be ground. These stop blocks may be readily mounted on the front of the table 21 in setting up the machine for grinding a given work piece.

The operation of this mechanism will be readily apparent from the foregoing disclosure. A multi-

stepped stop bar 85 corresponding to the work piece to be ground is mounted on the front edge of the table and is positioned longitudinally thereon to correspond with the work piece when mounted upon the headstock center 25 and footstock center 27. The machine may then be operated in the usual manner, that is, the table traversed longitudinally to position the desired portion of the work piece in operative relation 10 with the grinding wheel, and the wheel may then be fed into the work by rotation of the manually operable feed wheel 70. Unless the table has been moved to position the proper portion of the work in operative relation with the grinding wheel, the wheel cannot be fed in due to the fact that the stop block or lever 90 will engage a portion of the stop bar 85 and prevent feeding the grinding wheel into the wrong portion of the work piece. Similarly, the table 21 cannot be traversed 15 longitudinally to bring a larger diameter portion of the work into operative relation with the grinding wheel until the grinding wheel slide has first been moved rearwardly a sufficient distance so that the work piece will clear the grinding wheel when the table is traversed longitudinally. 20 25

It will thus be seen that there has been provided by this invention apparatus in which the various objects hereinabove set forth together 30 with many thoroughly practical advantages are successfully achieved. As many possible embodiments may be made of the above invention and as many changes might be made in the embodiment above set forth, it is to be understood that 35 all matter hereinbefore set forth or shown in the accompanying drawings is to be interpreted as illustrative and not in a limiting sense.

We claim:

1. In a cylindrical grinding machine, a rotatable grinding wheel, a transversely movable slide therefor, a longitudinally movable table, a rotatable work support thereon including a headstock and a footstock, means to traverse said table longitudinally, a feeding mechanism to feed said wheel slide transversely toward and from said work table to grind a work piece supported thereon, a multi-stepped stop bar which is adjustably mounted on said table, a moveable stop lever associated therewith, and means actuated automatically in timed relation with the feeding mechanism to cause a relative approaching and receding movement between said stop lever and bar. 45

2. In a cylindrical grinding machine, a rotatable grinding wheel, a transversely movable slide therefor, a longitudinally movable work table, a rotatable work support thereon including a headstock and a footstock, means to traverse said table longitudinally, a feeding mechanism to feed said wheel slide transversely successively to 50

grind spaced multi-diameter portions on a work piece, a safety device including a multi-stepped stop bar and a stop arm which are moved relatively toward and from each other, and operative connections between said feeding mechanism and said safety device whereby the stop arm is moved thereby so as to prevent a longitudinal or traversing movement of the table to position a larger diameter portion of the work piece in operative relation with the wheel until the wheel has been 10 moved rearwardly to a predetermined extent. 5

3. In a cylindrical grinding machine, a rotatable grinding wheel, a transversely movable slide for said wheel, a longitudinally movable work table, a rotatable work support thereon including a headstock and a footstock, means to traverse said table longitudinally, a nut and screw feed mechanism to feed said slide transversely, a manually operable feed wheel to rotate said screw, and a stop device including a stepped bar 20 on said table and a movable member actuated automatically by said feed wheel to stop the infeeding movement of the grinding wheel before it engages the work piece unless a predetermined portion of the work piece is in operative relation 25 with the grinding wheel. 25

4. In a cylindrical grinding machine, a rotatable grinding wheel, a transversely movable slide for said wheel, a longitudinally movable work table, a rotatable work support thereon including 30 a headstock and a footstock, means to traverse said table longitudinally, means to feed said grinding wheel slide transversely toward and from said table to grind a work piece supported thereon, a stepped bar adjustably mounted on said 35 table, and means including a pivotally mounted stop block which cooperates with said stepped bar and is actuated automatically by said feed mechanism to prevent an infeeding movement of the grinding wheel unless a predetermined portion 40 of the work piece is in operative position with relation to the grinding wheel. 40

5. In a cylindrical grinding machine, a rotatable grinding wheel, a transversely movable slide therefor, a longitudinally movable table having 45 a rotatable work support thereon, means to traverse said table longitudinally, a feeding mechanism to feed said wheel slide transversely, a multi-stepped stop bar adjustably mounted on said table, a movable stop lever associated therewith, a nut and screw mechanism to move said stop block and bar relatively toward and from each other, and means including a gear mechanism actuated automatically by said feeding mechanism to operate said nut and screw mechanism. 50 55
